UNITED STATES PATENT OFFICE

LAWRENCE E. CHURCHILL, OF OSHKOSH, WISCONSIN

DEVICE FOR BREAKING IN SMOKERS' PIPES

Application filed May 12, 1928. Serial No. 277,307.

This invention relates to a device for breaking in smokers' pipes, the general object of the invention being to provide a motor operated suction device which is adapted to be connected to a pipe by a flexible tube so that air will be drawn through the pipe to cause tobacco in the bowl of the pipe to burn, with means for periodically closing the circuit of the motor to cause the flow of air through the pipe so as to produce an intermittent suction through the stem and bowl of the pipe which simulates the action of a person using the pipe in the ordinary manner.

Another object of the invention is to provide a spring motor for operating the circuit closer and to provide a drum carrying advertising matter or the like which is rotated by the spring motor.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the device, with the interior parts shown in dotted lines.

Figure 2 is a plan view with the drum removed.

Figure 3 is a plan view with the cover of the casing removed to show the interior parts.

Figure 4 is a diagrammatic view of the circuit.

In these views, the numeral 1 indicates a casing which is provided with a removable cover 2 and in which is placed an electric motor M, the shaft of which is connected to a fan (not shown) placed in a casing 3 which is connected with the motor casing by the brackets 4. This fan casing 3 is provided with the usual inlet and outlet openings and the inlet opening is connected by a pipe 5, which passes through one side of the casing to a flexible hose 6 which is adapted to have its outer end placed over the mouthpiece of a pipe P which is supported by the member 7 which is shaped

to hold the pipe in a substantially upright position so that tobacco can be placed in the bowl of the pipe. Thus when the motor is in operation, a suction will be set up in the pipe 5 and tube 6 by means of the suction device 55 and thus air will be drawn through the pipe so that the tobacco in the bowl thereof will burn when lighted.

The circuit of the motor is shown at 8 and a hand operated switch 9 is attached to one of the outside walls of the casing to control said circuit. A second switch 10 is also placed in said circuit, the arm 10' of which is normally held in open position by the spring 11. A spring member 12 is attached to the switch 60 arm 10' and is insulated therefrom, as shown at 13, this member 12 being curved and provided with an offset part 14 which is adapted to be engaged by a pin 15 carried by a gear 16 once every revolution of the gear, the offset portion being of a length to cause the pin to hold the switch 10 in closed position for a short time during the revolution of the gear so that the circuit of the motor will be closed 70 and the motor will start up and thus cause the suction device to draw air through the pipe. After the pin passes off the offset part, the spring will open the switch and thus stop the motor. The gear 16 is fastened to a shaft 17 journaled in the cover 2 and having its upper 75 end extending above the cover, with its lower end being journaled in the frame 18 of a spring motor, the spring of which is shown at 19. A gear 20 is connected with the shaft 21 of the spring and a gear 22 on a shaft 23 meshes with the gear 20 and this shaft 23 has a pinion 24 at its upper end which meshes with the gear 16 so that said gear is driven 80 by the spring motor.

The spring 19 may be wound through means of a suitable handle placed on the outer end of the shaft 25 which is connected with the spring motor by the worm gear 90 ing 26.

A drum 27 carrying advertising matter or the like is placed on a wheel-like member 28 which is attached to the upper end of the shaft 17 and has a pin 29 thereon for engaging a hole in the bottom of the drum so that 100

the drum will be revolved from the spring motor.

From the foregoing it will be seen that as the spring motor revolves, it will cause the pin on the gear 16 to contact the member 12 once every revolution of the gear so as to close the circuit of the electric motor and thus bring the suction device into operation to cause a flow of air through the pipe. Then 10 after the pin passes off the offset part of the member 12, the spring will open the switch and thus stop the suction action. Thus the "draw" on the pipe is intermittent so as to simulate the smoking action of a pipe user. 15 Thus a new pipe will be broken in without the user being put to the discomfort of using a new pipe. At the same time, the drum will be revolved to attract attention to the device and to the advertising matter on the drum. 20 By closing the circuit of the motor, but once each revolution of the gear 16, the pipe will have ample time to cool off between puffs.

It is thought from the foregoing description that the advantages and novel features 25 of my invention will be readily apparent.

It is to be understood that I may make changes in the construction and in the combination and arrangement of the several parts, provided that such changes fall within 30 the scope of the appended claims.

What I claim is:—

1. A device for breaking in a smoker's pipe comprising a suction device, a hose for connecting the same with the mouthpiece of 35 a pipe, an electric motor for operating the suction device, a circuit for the same, a spring motor, a normally open switch in the circuit and means operated by the spring motor for moving the switch to closed position intermittently.

2. A device for breaking in a smoker's pipe comprising a suction device, a hose for connecting the same with the mouthpiece of a pipe, an electric motor for operating the suction device, a circuit for the same, a spring motor, a gear driven thereby, a pin eccentrically arranged on the gear, a normally open switch in the circuit and an arm connected with the switch and having a part engaged by the pin once during each revolution of the gear whereby the switch will be closed for a short interval and opened for a long interval during each revolution of the gear.

3. A device for breaking in a smoker's pipe comprising a suction device, a hose for connecting the same with the mouthpiece of a pipe, an electric motor for operating the suction device, a circuit for the same, a spring motor, a gear driven thereby, a pin eccentrically arranged on the gear, a normally open switch in the circuit, an arm connected with the switch and having a part engaged by the pin once during each revolution of the gear whereby the switch will be closed for a

short interval and opened for a long interval during each revolution of the gear, and a drum having advertising matter thereon rotated from the spring motor.

In testimony whereof I affix my signature. 70
LAWRENCE E. CHURCHILL.
